CLAIM

The ornamental design for a handle straw lid, as shown and described.

DESCRIPTION

FIG. 1 is a perspective view of a handle straw lid showing my new design;

FIG. 2 is a front elevational view thereof;

FIG. 3 is a back elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is another perspective view thereof, shown with the handle lifted in a configuration of use for clarity of disclosure.

The portions of the hand straw lid shown in broken lines form no part of the claimed design.

1 Claim, 8 Drawing Sheets
